Primary Examiner — Bridget L Eland(74) *Attorney, Agent, or Firm* — McDonnell Boehnen Hulbert & Berghoff LLP(57) **CLAIM**

The ornamental design for balloon dilation device, as shown and described.

DESCRIPTION

FIG. 1 is a perspective view of a balloon dilation device showing our new design.

FIG. 2 is a first side elevation view of the balloon dilation device of FIG. 1.

FIG. 3 is a second side elevation view of the balloon dilation device of FIG. 1.

FIG. 4 is a front view of the balloon dilation device of FIG. 1.

FIG. 5 is a rear view of the balloon dilation device of FIG. 1.

FIG. 6 is a top view of the balloon dilation device of FIG. 1; and,

FIG. 7 is a bottom view of the balloon dilation device of FIG. 1.

The broken lines in the drawings show portions of the balloon dilation device that form no part of the claimed design.

1 Claim, 4 Drawing Sheets(56)
